(57) CLAIM

I claim the ornamental design for a wall mounted golf club rack, as shown.

DESCRIPTION

FIG. 1 is a perspective view of the wall mounted golf club rack;

FIG. 2 is a front view of the invention;

FIG. 3 is a side view from the right of FIG. 2;

FIG. 4 is a side view from the left of FIG. 2;

FIG. 5 is a top view;

FIG. 6 is a bottom view; and,

FIG. 7 is a rear view.

The broken line showing is for illustrative purposes only and forms no part of the claimed design.
